UNITED STATES PATENT OFFICE.

WILLIAM H. FORSE, JR., OF ANDERSON, INDIANA.

CATCH PULLEY.

Application filed March 7, 1927. Serial No. 173,235.

This invention relates to a curtain cord cam pulley lock construction of the general character shown in Patent No. 711,570, dated October 21, 1902 to Hover.

5 The chief object of this invention is to produce from sheet metal a pulley support of the character shown in the before mentioned patent.

The chief feature of the invention consists 10 in the formation from a single strip of sheet metal a cam locking pulley support comprising a pair of ears and a base extending across the same and projecting laterally beyond said ears with return and inwardly directed extensions which are integral with the ear forming portions.

Another feature of the invention consists 15 in the provision of a laterally positioned base portion for forming an angle bracket base like Patent No. 711,570.

Still a further feature of the invention consists in the formation of the ears by a pair of return bend extensions, the inner extensions extending angularly of the ear portions 20 and towards each other and terminating short of abuttable relation for forming a cord locking groove.

The full nature of the invention will be 25 understood from the accompanying drawings and the following description and claims:

In the drawings Fig. 1 is a perspective view 30 of the simplest form of the invention. Fig. 2 is a developed plan view of the sheet metal strip forming the major portion of the invention. Fig. 3 is a perspective view of a slightly modified form of the invention. Fig. 4 is a developed plan view of the sheet metal blank required for the major portion thereof. Fig. 5 is a perspective view of still a further 35 modified form of the invention. Fig. 6 is a developed plan view of the sheet metal blank required to produce the major portion thereof. Fig. 7 is a perspective view of still a further modified form of the invention and 40 includes all the features shown in forms of the invention in Figs. 1, 3 and 5. Fig. 8 is a developed plan view of the sheet metal blank required therefor.

In the drawings 10 indicates a pulley wheel 45 having the spiralled grooves 11 thereon, the same being rotatably supported upon a pin 12 carried by a pair of ears 13 in the openings 14, whereby the pulley is supported in spaced relation to the back or base portion 15, the latter being shown channelled or provided 50 with a groove 16 to receive the sash or curtain

cord carried by the pulley. The base 15 is extended and projects laterally beyond the ears 13 and includes the anchorage receiving apertures 17. The ears 13 are connected to the base 15 by the inwardly extending portions 18 which constitute return bends of the base 15, and herein the same are shown provided with apertures 19 registering with apertures 17 for base anchorage purposes.

That form of the invention illustrated in Figs. 3 and 4 is substantially the same as that shown in Figs. 1 and 2, except that an auxiliary base 121 is provided and is of substantially the same length as the main base 115 and the groove 116 is extended as at 122 and the auxiliary base 121 is provided with the anchorage receiving openings 123 positioned substantially transversely of the anchorage receiving openings 117. The ears 113 are positioned transversely of both the main base 115 and the auxiliary base 122, and said ears are supported by said base 115 through the return bend portions 118 lying parallel to the main base and transversely of the auxiliary base. The resultant construction is fully as satisfactory for use as the device shown in the before mentioned patent.

The device shown in the before mentioned patent is a casting and requires considerable metal in order to form the angle bracket type and still more metal to form the same in the flat strip type such as shown in Figs. 1 and 2. The formation of the pulley supporting member from sheet metal permits the material to be utilized with a minimum of waste, for that form of the invention shown in Figs. 1 and 2 can be formed from a single width strip and that form shown in Figs. 3 and 4 can be formed from a strip of multiple width, each blank being substantially T-shaped and adjacent blanks being inverted as shown by the dotted line extensions so that no waste results therefrom. All of the blanks can be formed in suitable dies as required, that is, by one or more operations. The resultant construction is such that the base portion from the ear to the end is reinforced by the intermediate return bend connecting portion connecting the ear to the base and the base portion between the ears is reinforced in a way by the pin 12 supporting the catch pulley 10 so that the resulting construction is reinforced substantially the full length of the sheet metal base.

By reason of the formation of the groove 16 or its equivalent in the strip of sheet

metal, said sheet must be of suitable thickness or gage. Where it is desired to employ a lighter gage material the invention may be formed as set forth in Figs. 5 and 6. In 5 this form of the invention the base 215 is apertured as at 217 for receiving suitable anchorage means and the ear portions 213 are apertured as at 214 and are connected to the base portion 215 by the return bend portion 218 including the registering apertures 219. The ears, however, include a return bend portion 225 with apertures 226 registering with apertures 214 to receive the pin 12 supporting the pulley 10. Extending angularly of the ear return bend portion 225 and inwardly towards each other and parallel to the base portion 215 are the extensions 227 which may have suitably tapered edges 228 to form therebetween a groove 229, the full equivalent of groove 16. It will be apparent that very much lighter gage metal may be employed in this form of the invention than that shown in Figs. 1 to 4 inclusive, since the ears are reinforced and the base is reinforced substantially throughout its length, that is, no point in the base is weakened by milling, grooving or the like.

20 Figs. 7 and 8 show a modified form of the invention shown in Figs. 5 and 6, and in this form integral with the base is a blank portion 321 having apertures 323 therein. The auxiliary base 321 is adapted to be positioned at right angles to the main base 315 forming an angle bracket base.

25 35 As set forth previously with reference to Figs. 1 to 4 inclusive, the invention shown in Fig. 5 is formed from a single width strip, and the invention shown in Figs. 5 and 7 is formed from a multiple width strip with no waste since the adjacent blanks are inverted as indicated by the dotted lines, each blank being substantially T-shaped.

The invention claimed is:

1. A mounting for a pulley wheel comprising an elongated sheet metal strip having an intermediate base forming portion, a pair of ear forming portions integral therewith and positionable at right angles to the base form-

ing portion for rotatably supporting said pulley wheel in spaced relation to the base 50 portion, said base portion projecting laterally of and beyond the ear portions, and an intermediate connecting portion constituting a return bend lying parallel to and reinforcing said base portion and connecting 55 each ear to the base portion, each ear portion including a return bend portion extending from the free end of the ear toward the base and terminating in abuttable relation therewith for reinforcing said ear, each ear return bend portion including an angular extension lying parallel to said base portion within the pulley receiving channel formed by the ears, each extension terminating short of the other to form a cord receiving groove 60 65 therebetween.

2. A mounting for a pulley wheel comprising an elongated sheet metal strip having an intermediate base forming portion, a pair of ear forming portions integral therewith and 70 positionable at right angles to the base forming portion for rotatably supporting said pulley wheel in spaced relation to the base portion, said base portion projecting laterally of and beyond the ear portions, an intermediate connecting portion constituting a return bend lying parallel to and reinforcing 75 said base portion and connecting each ear to the base portion, each ear portion including a return bend portion extending from the free end of the ear toward the base and terminating in abuttable relation therewith for reinforcing said ear, and an auxiliary base portion integral with the main base portion and extending angularly thereof and 80 angularly of the angularly extending ears, each ear return bend portion including an angular extension lying parallel to said base portion within the pulley-receiving channel formed by the ears, each extension terminating short of the other to form a cord-receiving groove 85 90 therebetween.

In witness whereof, I have hereunto affixed my signature.

WILLIAM H. FORSE, JR.
